UNITED STATES PATENT OFFICE

LENA ROGERS HALL, OF MIAMI, FLORIDA

BELT-TURNING BODKIN

Application filed July 2, 1927. Serial No. 203,220.

This invention relates to a bodkin and more especially to an instrument of this character for use by dressmakers and clothing manufacturers.

5 In the formation of tubular belts, the cloth is folded upon itself lengthwise and stitched along one edge, leaving the raw stitched edge or seam exposed to view. Different methods are resorted to for turning this seam in the 10 inside, such as by stitching a hairpin to one end of the tubular belting thus formed, and passing it through the tubular body, turning the belting right side out; or by fastening a safety pin to one end of the tubular body and threading it through the tubular belting so as to turn the right side out. Also, in the threading of a tape or band through a hem these old and former makeshift methods have been resorted to. These 15 methods have their disadvantages, and their use is not always desirable with certain materials. The particular operation is not only a tedious one, but frequently a very difficult one and should the improvised bodkin accidentally become released from the end as it 20 is being pulled through, it is almost impossible to catch this end again without starting the operation anew.

The present invention has for its objects 25 to provide an improved bodkin which will facilitate and expedite the turning of a tubular fabric, or the threading of a tape or band through a hem; to provide a novel attaching means for securing the bodkin to the material to be pulled or led through; to provide a bodkin with a reversible clamping means for the material to be acted upon whereby the clamping means may be set in a 30 definite manner according to the direction of inserting the bodkin either by pushing or pulling the same through the tubular fabric; and to provide a readily flexible bodkin of an elongated form or design with a 35 clamping part of element so arranged as to be readily manipulated even after the bodkin has been inserted within the tubular fabric.

The invention is further found to reside 40 in the salient features of construction hereinafter described and claimed, reference be-

ing had to the accompanying drawing, wherein,

Fig. 1 is a side elevation of the improved bodkin.

Fig. 2 is a plan view thereof.

Fig. 3 is a fragmentary showing depicting the bodkin as being pushed through the tubular belting.

Fig. 4 is a similar view depicting the bodkin being pulled through the tubular belting.

Proceeding in accordance with the present invention, the numeral 1 designates the body of the bodkin which is preferably formed from a thin strip of steel or other light and readily resilient or yieldable material, such as celluloid. The body 1 at its rear end is deflected or sprung to one side to form a resilient jaw 2 for cooperating with a companion and resilient jaw 3 which is secured at its base to the body 1 in a desired manner, such as by the rivets 4. The inherent resiliency or tendency of the jaws 2 and 3 is to separate one from the other and this separating tendency is restricted or confined by a keeper 5, which, when the jaws are normally inoperative, rests in a pair of oppositely and outwardly facing concaved seats 6. These seats are preferably formed by bowing the shanks of the jaws inwardly to such a depth as to bring the keeper 5 substantially within the body lines of the jaws 2 and 3 thereby locating the keeper out of substantial contact with the material when idling through a hem or other tubular body. The walls of the seat 6 incline outwardly and thereby provide cam parts 6' which rise from the seat and on which the keeper may selectively ride to bring the jaws together or into clamping relation. The jaws 2 and 3 are reduced in width adjacent and on opposite sides of the seat 6, as indicated at 7, so as to provide forward stop shoulders 8 and rear stop shoulders 9 to be engaged by the keeper 5 when in its operative position and prevent accidental displacement of said keeper. The shoulders 8 and 9 extend out coextensive with the width of the keeper 5 so that the keeper does not project beyond the marginal edges of the jaws 2 and 3. Thus the keeper is al-

ways within the marginal edges of the jaws 2 and 3 so as not to engage or catch in the material being turned. The free ends 10 of the jaws 2 and 3 converge beyond the keeper 5 to provide the active portion of said jaws, these active portions being brought together in clamping relation by sliding the keeper in either direction from its seat 6. By reason of the fact that the keeper may 10 be slid in either direction from its seat-engaging position, a firm and secure clamping of the jaws will be insured regardless of whether the bodkin is pushed or pulled through the tubular hem or body. Thus in Figure 3, 15 where it is desired to push the bodkin through with the jaws leading, the keeper is moved against the forward shoulders 8 where it is securely held by the threading operation, since any manipulation to thread 20 the belting or hem over the jaws would bring more or less pressure on and frictional engagement with the keeper, which pressure would tend to further push the keeper against said shoulders 8. When it is desired 25 to pull the bodkin through, such as in Figure 4, the keeper is moved toward the shoulders 9 so that as the bodkin is pulled through the hem or tubular body, any frictional contact of the material with the keeper will only 30 tend to further press the keeper toward and against the shoulders 9 and thereby insure the keeper remaining in its operative position throughout the turning or threading operation. If for any reason the material 35 should slip from between the jaws 10 while the latter are concealed within the hem or fabric, it is a very easy matter to open the jaws by sliding the keeper 5 into the seat 6, working the end again between the jaws and 40 finally sliding the keeper into its operative position.

Frequently it is necessary to cover a cord or rope with the same material from which the dress is made and at the same time conceal the seam on the inside of the covering. This operation may very readily be performed by engaging the end of the cord by tacking or sewing the end of the cord to one side of the end of the belt, and then clamp 45 the jaws 10 down onto the engaged end of the belt, following which the tubular belt or body may be stripped over the bodkin onto the rope or cord.

The bodkin may be manufactured very economically, and the disposition of the keeper insures the firm engagement of the jaws with their attached end of the belting throughout the turning or stripping operation. If the bodkin is being pulled through the belting 55 or hem, the keeper is then engaged with the shoulders 9 so that any frictional contact or engagement of the fabric with the keeper will only tend to more securely hold the keeper in its operative position. This is equally 60 true with respect to an operation in which

the bodkin is being pushed through a hem or tubular belting. The keeper is preferably square so that if it should accidentally turn about the reduced portion 7 it will not become accidentally or unauthorizedly displaced. 70

After the belt has been turned, if the bodkin is on the inside thereof, the jaws may readily be unclamped from the cloth or fabric by a slackening up on the cloth about the keeper and then pushing the keeper into its recesses 6 following which a slight pull at the end of the belt will withdraw the same clear of the jaws and permit the bodkin to be readily removed. 75

While the bodkin is especially adapted for the turning of tubular belts and the threading of a tape or band through a hem, its utility is not limited to these particular functions since it has a wide application in the 80 dressmaking and seamstress arts. 85

I claim:

1. A bodkin comprising a flexible strip-like body having spaced jaws at one end normally spaced apart, said jaws having forward and rearward stop shoulders with an intermediate depression, and a keeper embracing the jaws and adapted to be engaged in the depression when in an inoperative position and selectively movable against either the forward or the rearward stop shoulders when in an operative position for effecting a clamping of the jaws. 90

2. A bodkin comprising a resilient strip having one end portion sprung outwardly to form a jaw, a cooperating jaw formed of a resilient strip and secured at its inner end to the first strip, one of said jaws being bowed outwardly from the other jaw with the free ends of said jaws relatively converging toward one another, and said bowed jaw having a depression intermediate its length forming a keeper seat, and a keeper engaged in said seat and movable therefrom in either direction lengthwise of the jaws for bringing the free ends of the jaws into clamping relation to each other. 100

3. A bodkin comprising a yieldable elongated body having a jaw on one end, a cooperating jaw secured to the body in opposition to the first jaw, one of said jaws having a keeper seat and a cam rising from each side thereof, stops at the remote ends of the cams, and a keeper engaged in said seat and movable therefrom along either cam to bring the active portions of the jaws into clamping relation to each other, said keeper being engageable with said stops to hold the keeper operative. 115

4. A bodkin comprising an elongated body having a jaw, a second jaw secured to the body for cooperating with the first jaw, each jaw having a shank with a depression therein forming a keeper seat, and a keeper engaged in said seat and movable in either di- 125 130

rection therefrom to bring the active portions of the jaws into clamping relation to each other.

5. A bodkin comprising a strip-like body having a jaw formed on one end, a second jaw secured to the body in cooperating relation with the first jaw, said jaws having shanks with reduced portions, and a keeper embracing the shanks about their reduced portions, 10 one jaw having a depressed seat and an adjacent cam part in its reduced portion and on which said keeper is movable for bringing the jaws into clamping relation.
